UNITED STATES PATENT OFFICE.

JOHN D. LEMEX AND CHARLES E. GALLMAN, OF TULSA, OKLAHOMA, ASSIGNORS TO
OIL WELL SUPPLY COMPANY, OF PITTSBURGH, PENNSYLVANIA, A CORPORATION
OF PENNSYLVANIA.

SLACK TUB.

Application filed November 13, 1923. Serial No. 674,540.

This invention is for an improvement in a slack tub for use in the field in connection with the quenching and tempering of tools.

It is common practice in the oil fields to use a receptacle for water, known in the art as a slack tub, into which drilling tools are dipped to be tempered after having been dressed.

The tool dresser in the oil fields is not generally skilled in the tempering of steel, and this, together with the improper design of the tubs now provided, results in a large quantity of steel bits being ruined by inefficient tempering.

The present invention proposes to provide a tub particularly designed for use in the field, which will facilitate proper manipulation of the tool in the tub and bring the cold water to the cutting edges of the bit, insuring more even and efficient tempering of the bits.

Other objects of the invention are to provide a tub of simple construction which may be cheaply manufactured and easily cleaned, and which will not be readily upset during the manipulation of the tools therein.

The invention may be readily understood by reference to the accompanying drawings, in which:

Fig. 1 is a top plan view of a tub embodying our invention; and

Fig. 2 is an end view of the tub.

The bottom 5 and sides 6 of the tub are formed from a single sheet of rolled steel, to which the end plates 7 are secured. The sides 6 are preferably inclined, so that the tub is wider at the bottom than at the top.

Secured in the tub on each of the end plates are cleats 8 having sockets 9 therein for the reception of parallel pipes or other suitable tool rests 10. These sockets are so arranged that the rests 10 may be lifted out whenever it is desired to do so. The rests extend longitudinally of the tank, and are well below the water line, indicated in Fig. 2 by the dot and dash line.

Resting on the bottom of the tank is a water distributing outlet 11, preferably in the form of a perforated pipe. Connected with water outlet 11 is a horizontal supply pipe 12 leading to one corner of the tank, where it is joined to a vertical pipe B adapted to be joined at its upper end to a source of water or other tempering fluid supply.

The water distributor and associated pipes are so arranged that they may be removably set in the bottom of the tub with the distributor substantially centered.

A water overflow is provided at 14, near the top of the tank, and a removable plug 15, near the bottom, is provided to enable the tub to be drained for cleaning or other purposes.

The tub may have structural bars 16 secured to the bottom thereof to provide skids 65 and to keep the bottom of the tub off the ground.

In use, the heated tool is lowered into the tub until it is supported on the rests 10. It is lowered in such manner that its lower end 70 will be just above the water or tempering fluid distributor 11. The cold incoming fluid will, therefore, be directed against the bottom of the bit just where it should come for the most efficient results. The warm 75 water flows out the top through the outlet 14.

By reason of the tank being wider at the bottom, it is not easily upset during the manipulation of the bit around the tub, and consequently, the bit may be manipulated 80 with greater ease in that the tool dresser need not fear the tipping over of the tub. The inlet water distributor and the rests are easily removable and replaceable, consequently, the tub may be easily cleaned. 85

We claim as our invention:

1. A slack tub comprising a bottom, side, and end members, the side members being inclined toward each other whereby the tub is wider at the bottom than at the top, removable tool rests within the tub, supporting means on the end members for the tool rests, and means positioned below the tool rests for introducing tempering fluid into the tub below the said rests. 95

2. A slack tub comprising a receptacle having an integral bottom and sides, the sides being inclined toward each other, whereby the tank is wider at the bottom than at the top, vertical end members for the tank, a cleat on each end member, tool supporting means removably retained on the cleats extending from one end of the tank to the other, and centrally positioned means below the supporting means for introducing tempering fluid into the receptacle below the supporting means. 105

3. A slack tub comprising a receptacle

having an integral bottom and sides, the sides being inclined toward each other, whereby the tank is wider at the bottom than at the top, vertical end members for the tank, a cleat on each end member, tool supporting means removably retained on the cleats extending from one end of the tank to the other, centrally positioned means below the supporting means for introducing

tempering fluid into the receptacle below the supporting means, and structural bars secured to the bottom of the receptacle and providing skids therefor.

In testimony whereof we affix our signatures.

JOHN D. LEMEX.
CHARLES E. GALLMAN.
